ADJUSTABLE SHOWER HEAD

Herbert Harvey, Los Angeles, Calif., assignor to
Leo M. Harvey, Los Angeles, Calif.

Application October 20, 1947, Serial No. 780,817

2 Claims. (Cl. 299—141)

1

This invention relates to an adjustable shower head and it is a general object of the invention to provide a simple, effective, improved head or nozzle construction, particularly useful in showers or the like.

In shower bath installations it is usually desirable to provide an adjustable shower or spray head. Such devices have been of various designs and constructions and are generally characterized by rather bulky, expensive and inconvenient structures subject to becoming clogged and stuck so that they cannot be adjusted.

It is a general object of the present invention to provide an effective, fully adjustable shower head involving few simple inexpensive parts. The construction of the present invention involves only one part requiring operation or movement to effect full adjustment and this part is of very simple form and construction.

A further object of the invention is to provide a construction of the general character referred to in which the adjusting element is so located that it can be engaged and operated without intersecting the path of the spray issuing from the head, all with the result that adjustment can be made while the true action of the head is observed and without causing undesirable splattering of water.

Another object of the present invention is to provide a shower head of the general character referred to wherein the adjusting member is of sturdy form and construction and is such that it can be firmly gripped for operation. The operating or adjusting member of my construction presents a large surface that can be conveniently gripped giving the operator effective purchase so that adjustment can be made with a minimum of effort.

A further object of my invention is to provide a head of the general character referred to in which the few parts involved are so organized and related that they can be assembled easily and quickly and are held against separation when the structure is installed for operation.

The various objects and features of my invention will be fully understood from the following detailed description of a typical preferred form and application of the invention, throughout which description reference is made to the accompanying drawings, in which:

Fig. 1 is a side elevation of the head provided by the present invention showing it in one position or setting. Fig. 2 is a longitudinal sectional view of the structure shown in Fig. 1, being a view taken as indicated by line 2—2 on Fig. 1. Fig. 3

2

is a view of the lower end portion of Fig. 1, showing another position or setting of the device. Fig. 4 is an enlarged transverse sectional view of the structure taken as indicated by line 4—4 on Fig. 1. Fig. 5 is an enlarged sectional view taken as indicated by line 5—5 on Fig. 4 and Fig. 6 is an enlarged sectional view taken as indicated by line 6—6 on Fig. 4.

The structure provided by my present invention involves, generally, a body A, a sleeve B and a mounting means C for the body.

The body A is an elongate member with a central bore 10 entering it from the upper end and terminating short of the lower end, leaving the lower end of the body closed by a bottom 11. An annular recess 12 is provided in the exterior of the body forming an annular chamber spaced somewhat from the lower end of the head, leaving a projecting part in the form of a radially projecting flange 13. The flange 13 has a round peripheral surface 14 concentric with the longitudinal axis of the body and in the case illustrated it is formed to have a flat upper end 15. The lower end 16 of the flange portion 13 is shown pitched to extend somewhat upward and outward. A plurality of radial ports 17 connect the bore 10 with the recess 12, the ports 17 being of such size and number that the annular chamber established by the recess 12 is, in effect, a part of the central opening or cavity in the body A established by the bore 10.

A thread 20 is formed on the exterior of the body above the recess. In accordance with my invention the thread 20 extends from a point near the recess 12 to the upper end of the body A, but is interrupted intermediate its ends with a somewhat reduced or smooth portion 21 dividing the thread into upper and lower sections. A packing recess 22, is provided in the exterior of the body between the lower end of the thread 20 and the recess 12.

In accordance with my invention a plurality of longitudinal channels 30 and 31 are formed or provided in the peripheral portion of the flange 13 so that they extend downwardly and outwardly in the flange from the recess 12 or from the upper end 15 of the flange to the lower end portion of the flange where they terminate at or die into the peripheral surface 14 of the flange. In accordance with my invention the channels 30 and 31 are circumferentially spaced and may be uniformly spaced as shown in the drawings and the several channels may be of uniform width. I prefer, however, that the channels 30 be inclined at a greater angle than channels 31 so that their

bottoms 30^a are pitched greater than the bottoms 31^a of the channels 31 or extend deeper into the flange than do the bottoms 31^a. In the preferred arrangement the channels 30 and 31 are in equal number and are arranged alternately as clearly illustrated in Fig. 4 of the drawings. It is desirable in practice to form the channels 30 and 31 so that their lower ends all terminate in a common plane or the same distance above the bottom end 16 of the flange 13. In the particular case illustrated the channels are formed so that they have flat parallel sides. However, it will be understood that by changing the shape or cross sectional configuration of the channels varying jet actions may be obtained.

The sleeve B of the construction is a simple tubular part with its upper end portion provided with an internal thread 40 and with a depending middle portion 41 that extends down over the packing recess 22 to the recess 12 and with a lower lip portion 42 depending from the lower end of the middle portion 41. The threads 40 of the upper portion of the sleeve are carried on the lower threaded section of the thread on body A. The middle portion 41 of the sleeve has a smooth or turned inner surface 44 providing a smooth surface to be engaged by a packing ring 45 carried in the recess 22. The middle portion 41 depends below the packing ring to overlie a portion, at least, of the recess 12.

The lip portion 42 of the sleeve is, in effect, a continuation of or a depending part on the lower end of the sleeve portion 41 and it has a smooth turned interior 46 slidably fitting over the peripheral surface 14 of the flange 13. The extent to which the lip 42 extends over or overlies the flange 13 varies depending upon the position of the sleeve B on the body A, which adjustment can be readily varied by rotating the sleeve to move it either up or down on the body, as desired. The lip 42 serves to more or less choke or throttle the flow through the channels 30 and 31 and it will be apparent that when the lip is in a position such as is shown in Figs. 1 and 2, the channels are uncovered so that substantial flow occurs therethrough, whereas when the lip is in a lowered position such as is shown in Fig. 3, the channels are almost covered, with the result that only fine streams can issue therefrom.

It is important to note that the exterior of the sleeve B is of considerable extent, being of substantial diameter and of considerable extent lengthwise of the structure, so that it provides a part that can be readily and conveniently gripped by the operator. In practice the exterior of the sleeve may be provided with any suitable means to prevent slippage of the hand on the sleeve. For example, as shown in the drawings, it may be provided with one or more sections 50 knurled or otherwise finished to facilitate a sure grip.

In accordance with the preferred form of my invention I provide a stop means to limit downward movement of the sleeve on the body so that the sleeve cannot be separated or detached from the body by excessive operation of the sleeve. In the case illustrated a downwardly facing stop shoulder 61 is provided in the sleeve at the point where the middle portion 41 of the sleeve joins the lip 42. The desired shoulder can be conveniently established by making the opening 46 in the lip slightly larger in diameter than the opening 44 in the middle portion 42. When the sleeve has been screwed down as far as desired the stop shoulder 61 engages the upper end 15 of flange 13, thus positively stopping further

downward movement of the sleeve or separation of the sleeve from the body. When this construction is employed the parts are arranged and proportioned so that the sleeve B is applied to the body A so that it assumes the desired position as shown in the drawings by threading the sleeve onto the body from the upper end of the body prior to the means C being assembled with the body.

10 The mounting means C is preferably a universal joint construction allowing for positioning of the body A at various angles relative to a supply pipe P, or the like. I have shown a simple ball and socket type of mounting means involving, 15 generally, a coupling member with a coupling part 62 internally threaded at 63 to receive the pipe P. A projection 64 on the lower end of the coupling member 62 is in the form of a ball or at least has a spherical outer surface 65 while a central flow passage 66 extends through it so that 20 water from pipe P is supplied into body A. The upper end portion 70 of the body A is formed with a socket opening 71 to receive the ball projection 64 and a packing ring 67 is provided in the 25 socket 71 to make sealing engagement with the ball. A retainer or collar 73 is threaded on the body portion 70 or on the upper section of the thread provided on the exterior of the body. The collar has an upper inwardly projecting lip or 30 flange portion 74 that is smaller in diameter than the ball projection 64 and which engages the ball projection to hold it in the socket 71. In the case illustrated I provide a set screw 75 carried by the collar 73 to be engaged with the body to 35 set the collar in the desired adjusted position preferably so that there is enough frictional engagement between the body and ball so that the body will only move when deliberately operated.

From the foregoing description it will be apparent that I have provided a head construction for a shower or the like involving few simple easily formed parts. All of the parts of my construction are simple screw machine parts and the assembly of the parts is very simple. To make 40 the structure ready for use the packing ring 45 is arranged on the body and then the sleeve B is threaded onto the body from its upper end until it assumes a position such as is shown in Fig. 1 of the drawings. The ball projection 64 of means C is then arranged in the seat socket 71 whereupon the collar 73 is passed over part 64 and threaded onto the upper section of the body thread making the ball projection secure in the 45 socket. When the desired engagement has been established between the ball projection and the socket the set screw 75 is tightened whereupon the structure is ready for application to a pipe P or the like.

50 In use the channels 30 and 31 in the flange 13 direct streams of water downward and outward in planes parallel with the longitudinal axis of the structure, some of the streams issuing at a greater angle than others for the reasons hereinabove pointed out. The character of the spray obtained may be varied or adjusted at will by moving the sleeve B up or down on body A, and this can be done by reaching the sleeve B without intercepting the stream or spray issuing from the device.

Having described only a typical preferred form and application of my invention, I do not wish to be limited or restricted to the specific details herein set forth, but wish to reserve to myself 55 any variations or modifications that may appear

to those skilled in the art and fall within the scope of the following claims.

I claim:

1. A shower head including, a central elongate body with a bore extending into it from its upper end and terminating short of its lower end, the body having an outwardly projecting longitudinally channel flange at its lower end in communication with the bore, mounting means for the body, a sleeve on the exterior of the body and having a lip portion at its lower end concentric with and overlapping the flange controlling flow therethrough, threads between the sleeve and body at a point above the flange and stop means limiting downward movement of the sleeve on the body including a downwardly facing shoulder in the sleeve between the lip and threads and cooperating with the flange.

2. A shower head including, an elongate body having an annular recess in its exterior spaced from its lower end leaving an end flange with a longitudinally channelled periphery and having two longitudinally spaced exterior threaded portions above the recess and a bore entering its upper end, terminating short of its lower end and connected with the recess by radial ports, mounting means carried by the upper end portion of the body, a sleeve around the body engaged with the lowermost of said threaded portions on the exterior of the body, covering the recess and having an annular depending lip portion overlapping the flange, the mounting means including a fitting with a ball portion engaged

in a socket in the upper end of the body and a retaining collar engaged with the uppermost threaded portion of the body and holding the ball portions in the socket, stop means limiting downward movement of the sleeve on the body, upward movement of the sleeve on the body being limited by the collar, and packing carried by the body between the recess and the lowermost threaded portion and sealing with the interior of the sleeve, the threaded portions and the flange of the body being of substantially the same diameter.

HERBERT HARVEY.
